UNITED STATES PATENT OFFICE.

ARTHUR E. LEARY, OF SHREWSBURY, MASSACHUSETTS.

ADJUSTABLE SHADE-ROLLER DEVICE.

1,156,410.

Specification of Letters Patent.

Patented Oct. 12, 1915.

Application filed February 1, 1912. Serial No. 674,658.

To all whom it may concern:

Be it known that I, ARTHUR E. LEARY, a citizen of the United States, residing at Shrewsbury, in the county of Worcester and State of Massachusetts, have invented a new and useful Adjustable Shade-Roller Device, of which the following is a specification.

The principal objects of this invention are to provide a practicable means for permitting a shade roller to be brought bodily to any desired position below the top of a window, whereby the shade can be caused to cover any desired portion of the window, either at the top or bottom or part way between.

The invention also involves improved means whereby the roller can be rotated and raised and lowered in such a way as to be controlled by the manipulation of the shade itself, so that by raising and lowering the shade in a certain manner the shade can either be rolled up on the roller or the roller raised or lowered bodily.

The invention also involves improvements in the details of the supporting and guiding means for the shade roller, and in the means for controlling the rotation and reciprocation thereof and in other features of construction.

Further objects and advantages of the invention will appear hereinafter.

Reference is to be had to the accompanying drawing, in which—

Figure 1 is a perspective view of a window casing with a shade roller mechanism constructed in accordance with this invention applied thereto. Fig. 2 is a front elevation of the same partly in section; Fig. 3 is a side view of one of the side casings showing the shade roller spindle in section; Fig. 4 is a horizontal sectional view on the line 4—4 of Fig. 2; Fig. 5 is a horizontal sectional view on the line 5—5 of Fig. 3; Fig. 6 is a side view of the left hand shade support; Fig. 7 is an end view of one of the shade roller raising devices with the cover removed; Fig. 8 is a rear elevation of the drum thereof; and Fig. 9 is a central vertical sectional view of the same.

It is to be understood that the invention can be applied to a window casing in the building thereof without increasing the size or forming any projections thereon in the wood-work or that it can be applied to a casing already built by adding strips to the

side casings. It is shown as applied to a box casing. As illustrated the side casings 10 are provided with a pair of opposite cylindrical sockets 11 for receiving cylindrical casings 12. These casings have soldered to 60 the inner end thereof a flat projection 9 extending into the wood and secured by screws 8. Each of these casings is provided with a drum 13 on which is wound a flexible connection 14 shown in the form of a metallic tape, but it will be obvious that any other desired flexible connection can be used. Inside the drum and so wound up that when free to operate it will rotate the drum in a direction to entirely wind up the flexible 70 connection thereon is a coiled spring 15. This is fixed at one end to the drum and at the other to the stationary shaft 16. On the back of this drum is a one-toothed ratchet wheel 17 rotating with the drum and having a flat surface 18 adjacent to the tooth 19 thereof. A gravity pawl 20 is shown fixed on the casing 12 in such position that as the drum with the ratchet wheel is rotated in the direction of the arrow in Fig. 8 80 at a slow speed, the pawl will be caused to catch in the tooth 19 at every revolution so that the flexible connection will be stopped at definite points. However, if the device is manipulated so as to permit the spring to 85 rotate the drum and wheel rapidly the surface 18 will give the pawl a throw over the tooth 19 so that the drum will continue to rotate and the flexible connection will continue to ascend. This is a principle which 90 is well-known in shade rollers proper. It will be understood, of course, that both of these devices are designed in the same way but that they are right and left handed. However they are so designed that they will 95 both catch at the same time when the two flexible connections are raised together as they are designed to be.

At the bottom the two flexible connections are provided with holders 21 and 22 respectively. These holders operate in vertical slots or guides 23 and 24 respectively, shown as being located in the casing. The holder 21 is provided with a non-cylindrical slot 25 therethrough for a non-cylindrical spindle 26 of a shade roller 27. This shade roller is of an ordinary well known type and involves the usual wind spring 28 and gravity ratchet 29 by the non-cylindrical spindle 26. The only thing required is that this spring shall 110

be weaker than the springs 15, a matter that is controlled, of course, in the selection of the latter. The holder 22 is provided with a cylindrical passage 30 for a cylindrical spindle 31 of the shade roller. Both of these holders are provided with side flanges which operate in the undercut guides, as will be obvious, to keep them therein. The spindle 31 is provided with a non-circular portion 32 driven into the wood of the roller to hold it rigidly therein, the purpose of which will appear hereinafter. The outer end of the spindle 31 is provided with a diametrical open ended slot 33. This is to receive an edgewise movable bar 34 as indicated in Fig. 4. This bar is mounted to bear at its ends on a pair of spring members 35 and is normally forced into the dotted lined position in Fig. 5 by these and a spring 36 on a screw 37 secured to the bar in offset position. By screwing up a wing nut 38 on the screw, however, these parts can be brought up to the full line position in Figs. 4 and 5. The bar is guided by pins 39 passing through transverse slots 40 in the ends of the bars.

In operation, let it be assumed that the parts are in the position shown in Fig. 2, with the pawls 20 located against the teeth 19 so as to hold the shade roller in position. If the bar 34 is in the full line position, Figs. 2, 4 and 5, it is obvious that it will prevent the rotation of the spindle 31 and consequently of the shade roller itself. This is why the projection 32 is provided. Now it will be obvious that a pull on the shade cannot unwind the shade on its own roller, but will simply result in lowering the roller as a whole along the guides. This is done in a way that will be readily understood, the pawls 20 controlling the position at which the roller is left. Now if it is desired to raise or lower the shade on its roller without moving the roller, the bar 34 is moved out of the slot 33 by loosening the wing nut 38 and allowing the springs to force it back. When this is accomplished and the bar is in the dotted line position the manipulation of the shade will have the usual effect in raising and lowering it due to the ordinary spring-ratchet in the shade roller, and it can have no effect to raise and lower the shade roller because the spring in the roller is weaker than the springs 15. It will be seen therefore, that the manipulation of the device is extremely simple and that it is a very easy matter to bring the shade to any desired position so as to cover any desired portion of the window and yet there are few parts which are likely to get out of order in use or to cause any trouble in operation.

Although I have illustrated and described only one form of the invention, I am aware that the same principles can be carried out in other forms and that the invention is not

limited to the particular details of construction shown. Therefore I do not wish to be limited to such details, but

What I do claim is:—

1. In a shade roller device, the combination of a shade roller having a non-circular spindle and a circular spindle, said roller being vertically movable, and the circular spindle having a diametrical slot in its end, a bar movable edgewise into and out of said slot for controlling the rotation of said spindle, and means for moving the bar. 70

2. The combination of a shade roller spindle having a slot, a bar having a thin edge for entering the slot in the shade roller spindle, springs for pushing said bar away from the spindle, and a screw and nut for moving it in opposition to the springs. 80

3. The combination of a casing having a vertical slot therein, undercut along both sides and having a cylindrical socket at the top, a holder slideable in the undercut portion of the slot, a cylindrical casing mounted in said socket, having a flat projection thereon extending into the wood of the casing to keep it stationary, a winding drum in the cylindrical casing having means for raising said holder, and a shade roller having a spindle supported by the holder. 90

4. In a shade roller device, the combination of a vertically movable pair of holders for the ends of a shade roller, yielding means for elevating said holders, a shade roller having a spring ratchet device by which the roller can be held from rotating, 100 and external manually operated means for positively preventing the rotation of said shade roller, whereby when the positive means is in operation the roller can be raised and lowered by the manipulation of 105 the shade.

5. In a shade roller device, the combination of a pair of holders for the ends of the shade roller mounted to move up and down, a flexible connection for supporting a shade 110 roller having a non-cylindrical spindle and a cylindrical spindle, the non-cylindrical spindle being held from rotating in one of said holders, and the cylindrical spindle rotatably mounted in the other, said shade roller 115 having a spring ratchet device by which the roller can be held from rotating, and external manually operated means for positively preventing the rotatable spindle from rotating, whereby when the last named 120 means is in operation the roller may be raised and lowered by the manipulation of the shade.

6. In a shade roller device, the combination of a pair of vertically movable holders, 125 a shade roller having two spindles, one of them being held from rotating in one of said holders, and the other being rotatably mounted in the other, said shade roller having means by which the roller can be held 130

from rotating, means whereby when the shade is pulled from the roller it will unwind without lowering the roller itself, the rotatable spindle having a diametrical slot 5 in the end thereof, and a vertical bar movable edgewise into and out of said slot for controlling the motion of said spindle.

7. In a shade roller device, the combination with a shade roller having means controlled by the manipulation of the shade whereby a shade thereon can be held at different elevations, of means, also controlled by the manipulation of the shade, whereby the roller itself can be raised and lowered and held stationary at different elevations the last named means comprising a cylindrical spindle on one end of the roller having an open ended slot in the end thereof, and a vertical bar movable into the slot to 20 prevent rotation of the spindle and roller.

8. In a shade roller device, the combination of a vertically movable shade roller adapted to be held at different elevations, said shade roller having means whereby the shade thereon can be wound on and off the roller and held in different positions with 25

respect thereto, a spindle on the roller having an open ended slot in the end thereof, a bar movable edgewise into said slot, resilient means for normally moving the bar 30 out of the slot, and positive means for moving it into the slot.

9. The combination of a shade roller having a non-circular spindle on one end, and a circular one on the other, the circular 35 spindle being fixed to the roller and having an open ended slot in the end thereof, and means for entering said slot to prevent the rotation of the roller.

10. The combination of a spindle for a shade roller having a circular bearing portion and provided with an open ended slot in the end, and means for entering said slot to prevent the rotation of the roller.

In testimony whereof I have hereunto set 45 my hand, in the presence of two subscribing witnesses.

ARTHUR E. LEARY.
